UNITED STATES PATENT OFFICE.

MORTIMER C. ROSENFELD, OF CLEVELAND, OHIO.

ADJUSTABLE BEAM-CLAMP.

No. 893,378.

Specification of Letters Patent.

Patented July 14, 1908.

Application filed October 10, 1907. Serial No. 396,713.

To all whom it may concern:

Be it known that I, MORTIMER C. ROSENFELD, a citizen of the United States, resident of Cleveland, county of Cuyahoga, and State 5 of Ohio, have invented a new and useful Improvement in Adjustable Beam-Clamps, of which the following is a specification, the principle of the invention being herein explained and the best mode in which I have 10 contemplated applying that principle so as to distinguish it from other inventions.

My invention relates to adjustable beam clamps, its object being to provide a structure which may be economically manufactured and readily adjusted.

Said invention consists of means hereinafter fully described and particularly set forth in the claims.

The annexed drawing and the following 20 description set forth in detail, certain mechanism embodying the invention, the disclosed means constituting but one of various mechanical forms in which the principle of the invention may be applied.

25 In said annexed drawing:—Figure 1 represents an elevation of the two main clamping members showing the inner side of one and the outer side of the other. Fig. 2 represents a front elevation of the beam clamp 30 assembled. Fig. 3 represents an end elevation of the same. Fig. 4 represents a partial view of a beam clamp embodying a part of my invention, showing a modified form of clip. Fig. 5 represents a cross-sectional view 35 taken upon the plane indicated by the line V—V in Fig. 4.

The two main members A A are duplicates of each other, the outer ends of each being formed with a hook-portion a which together 40 with a seat portion a' receives the edge-portion of the I-beam flange, as will be readily understood. The inner side of the shank portion a^2 is serrated to form teeth a^3 . The other side of such shank-portion is provided 45 with a longitudinal groove a^4 .

In assembling the clamps the two members A A are placed with their serrated surfaces contiguous to each other and overlapping, as shown in Fig. 2. These overlapping portions 50 are secured to each other transversely by means of an open-ended clip B which is provided with inwardly curved jaws b whose extremities enter and slide in the grooves a^4 .

The one side of the clip is provided with a hole tapped out to receive a set-screw b' . 55 The said hole is made to lie opposite the lower portion of the contiguous member A and below the groove a^4 . It will therefore be seen that by turning the screw its inner end will engage the contiguous surface of the 60 member A thereby clamping the two members together transversely and causing the serrations to engage and secure the said two members against longitudinal movement.

By providing an open-ended clip and 65 grooves it will be seen that the clip may be slid on and off the members A without separating them, and the clip when engaged in the grooves will remain in place when the set-screw is loosened. It will further be 70 noted that the clip does not extend above the upper surface of the overlapping portion and hence offers no obstruction at that point.

In Figs. 4 and 5 I have shown a modified form of clip in which a screw C is used to 75 draw the two jaws together to engage the portion a^3 , the necessary elasticity being provided by the formation of a slot b^2 . The lower ends of the clip may be provided with a tapped-out hole, as shown, in which may 80 be secured a rod or other member which it may be desired to support.

Other modes of applying the principle of my invention may be employed, instead of the one explained, and change may be made 85 as regards the mechanism herein disclosed, provided the means covered by any one of the following claims be employed.

I, therefore, particularly point out and distinctly claim as my invention:—

1. In a device of the class described, the combination of two members adapted to be juxtaposed to overlap each other, the outer end portions of such members being formed to engage a beam, and the surfaces rendered 95 contiguous by such juxtaposition being serrated; the outer lateral faces of the overlapping portions of said members being each provided respectively with a groove, an open-ended clip slidable in said grooves, and 100 a set screw adapted, in conjunction with said clip to fix the two members transversely whereby said serrations are caused to be fixedly engaged.

2. In a device of the class described, the 105 combination of two members adapted to be

juxtaposed to overlap each other, the outer end portions thereof being formed to receive a beam, and the surfaces rendered contiguous by such juxtaposition being separated, the outer lateral faces of the overlapping portions being provided respectively with a groove; an open-ended clip slideable in said grooves; and a set screw mounted in

10
said clip and adapted to have its inner end engage the contiguous member.

Signed by me, this 23rd day of September, 1907.

MORTIMER C. ROSENFELD.
